UNITED STATES PATENT OFFICE.

LEE J. VOORHEES, OF BINGHAMTON, NEW YORK, ASSIGNOR TO NATIONAL CARBON COMPANY, INC., A CORPORATION OF NEW YORK.

SYMMETRICAL ROTATING SWITCH.

Application filed December 9, 1921. Serial No. 521,233.

This invention relates to electrical switches having a primary circuit-controlling mechanism, normally freely operable to open or close an electrical circuit, and having also locking means adapted, on proper manipulation, to place the primary mechanism in a position to either open or close the circuit, as desired, and to retain the primary mechanism in such position until further manipulation of the locking means. Such switches are applicable in general to electrical apparatus in which there is a circuit which must, under certain operating conditions, be frequently opened and closed, but which under other conditions must be closed for long periods of time. For the sake of illustration, the switch mechanism of the present invention will be described in connection with a portable self-contained battery hand lamp, of the kind commonly known as "flashlights."

The switch construction comprises broadly a fixed plate having a circular seat struck up therefrom and operable parts symmetrically disposed with respect to the seat. Arcuate slots are provided adjacent the periphery of the seat and a depressible, spring-supported push-button is rotatably mounted in the slots. The seat has elevated and depressed portions adapted to cooperate with a corresponding conformation in two plates rigidly attached to the push-button, one plate being disposed beneath, and the other plate above, the seat. The elevations and depressions are symmetrically arranged with respect to a central contact member which depends from the bottom plate. In the intermediate position of the switch, the spring-supported push-button may be freely depressed, and will be automatically returned to its original position upon removing the downward pressure. In the two extreme positions to which the button may be rotated, the engagement of the surfaces is such that the contact member is securely held either in or out of operative position.

An embodiment of the invention as applied to a common form of flashlight is shown in the accompanying drawings, in which

Fig. 1 is an elevation of a flashlight provided with the improved switch,

Fig. 2 is a plan view of the escutcheon plate and circular seat,

Fig. 3 is a plan view of the upper plate, Fig. 4 is a side elevation of the upper plate,

Fig. 5 is a perspective view of the push-button, before assembly with the other parts,

Fig. 6 is a top plan view of the contact plate,

Fig. 7 is a section on line 7—7 of Fig. 1, showing the assembled switch in "flash" position, and

Figs. 8, 9, and 10 are somewhat diagrammatic sectional views illustrating the relative position of the parts when the switch is in "flash," "on," and "off," positions, respectively.

Referring to the drawings, the switch assemblage is illustrated as applied over an aperture in a flashlight casing 1. A conductor connects one terminal of the battery with some portion of the switch, such as the escutcheon plate 2. One terminal of the filament of the incandescent bulb is connected with the other terminal of the battery, while the other terminal of the bulb is connected with a contact strip 3, passing beneath the aperture in the casing and hence beneath the switch.

Stamped in the escutcheon plate 2 is a circular seat 4 in the form of a truncated cone having the lateral wall 5. An external rotatable member 6 has a flat circular base 6' adapted to fit upon the seat, and a raised portion 7 around its periphery, from which portion a skirt 8 depends, overlying the lateral wall 5. This skirt may be suitably knurled or fluted so that it may be readily turned by the fingers. Arcuate slots 9 are cut in seat 4 adjacent its periphery to guide the travel of the rotating parts.

These parts comprise, beside the rotatable plate 6' already referred to, a metal shell 10 having a rounded top and three tongues 11 adapted to pass through slots 9. The base plate 6' is cut away at its margin sufficiently to receive the tongues, so that the shell and plate may rotate as a unit over seat 4. A circular contact plate 12 is formed to fit upon the under side of the seat. Narrowed terminal portions 13 of tongues 11 pass through marginal slots 14 in the contact plate and are bent inwardly as at 13' to pass beneath the plate. The contact plate is in

this manner supported beneath the seat 4 and made rotatable with the shell 10 and base plate 6'. Before assembling the parts as described, a spiral spring 15 (Fig. 7) is placed 5 under compression between the base plate 6' and the rounded top of shell 10. The latter is normally supported by the spring and is operable as a push-button to close the circuit, when the switch is in the position 10 illustrated in Figs. 7 and 8.

The means for retaining the rotatable parts of the switch in each of the three adjusted positions comprise series of cavities and projections formed in fixed seat 4 and 15 cooperating parts in rotatable base plate 6' and contact plate 12. Three conical cavities 16, 16' and 16'' are stamped in seat 4, symmetrically positioned with respect to the center of the seat. A conical projection is 20 struck up halfway between each two cavities. These projections, denoted by 17, 17', 17'', lie on the circumference of the circle passing through the centers of cavities 16, 16' 16''.

25 In base plate 6' there is a symmetrically arranged series of rounded bosses 18, 18', 18'', adapted to snap over projections 17, 17', and 17'' on seat 4, for a purpose to be explained. A series of elongated elevations 30 19, 19', 19'' is also formed in plate 6', the members of this series alternating with the members of series 18. The altitude of projections 17 is such that they may travel in elevations 19 in close engagement therewith.

35 The contact plate 12 has three symmetrically arranged trough-shaped depressions 20, 20' and 20'', cooperating with the portions of seat 4 struck downward to form cavities 16, 16', 16''. Said plate is also depressed centrally to form a conical contact member 21, adapted on proper manipulation 40 of the switch to engage conductor strip 3.

The operation of the switch will now be 45 described, having reference to Figs. 8, 9, and 10. In the "flash" position, Fig. 8, projections 17 and 17' on seat 4, are received in the elongated elevations 19 and 19' on rotatable base plate 6'. The projections lie adjacent the right hand end of the elongated elevations, in this position of the switch. Cavities 16 and 16' of the seat 4 lie in trough-shaped depressions 20 and 20' of the contact plate 12 and near the left hand end of those depressions. The frictional engagement between 55 17 and 19, 17' and 19', 16 and 20, 16' and 20', is sufficient to prevent accidental shifting of the parts. When the parts are so disposed, the push-button 10 may be freely depressed to bring projection 21 into contact with conductor strip 3, and will automatically return to the open circuit position when the pressure is removed. Upon depressing the button, tongues 11 descend 60 through slots 9 in seat 4, and contact plate 12, rigidly secured to the tongues by the

close fitting engagement of parts 13 and 14, or in any suitable manner, is thereby lowered into operative position.

To place the switch in "on" position (Fig. 9), it is rotated clockwise from the position 70 shown in Fig. 8. Such movement causes the walls of cavities 16 and 16' of the seat 4 to slide upward past the ends of troughs 20 and 20' to rest upon the plane surface of contact plate 12. The depth of 16 and 16' is such as 75 to afford depending walls capable of forcing the contact plate downward until the conical contact member 21 engages strip 3. Elongated elevations 19 and 19' move forwardly 80 over projections 17 and 17' until these projections lie near the left hand end of the said elevations. The compressive force exerted by the spring holds the parts in the described position until their position is changed by 85 manual rotation.

Counter-clockwise rotation of the switch from the position shown in Fig. 8, will place it in "off" position, (Fig. 10). Projections 17 and 17' on seat 4 pass out of elevations 19 and 19' and are snapped into rounded bosses 90 18 and 18' on plate 6'. At the same time, cavities 16 and 16' move to the right hand end of troughs 20 and 20'. In this position, the shoulder 22, formed by cutting away a 95 portion of tongue 11, passes beyond the end of slot 9 in seat 4. So long as the shoulder overlies the plate, it is obvious that the button can not be depressed. The frictional engagement of the parts holds them in adjusted position, as described in connection with 100 Fig. 8.

In the above description where only a part 105 of the members of any of the symmetrical series of locking members has been referred to, it will be understood that the remainder have the same mode of operation as those described.

It will thus be seen that when the member 6 is rotated as far as possible in one direction, the lamp will be lighted and can be extinguished only by rotating member 6 in the opposite direction. In its other extreme position, member 6 is positively retained in its elevated position. When member 6 is in its median position, the lamp is lighted by 115 pressing on the push-button and extinguished by releasing it. If less than three adjusted positions are desired, the switch mechanism may be modified by omission of parts to produce a satisfactory one-position 120 or two-position switch.

As has already been indicated, the application 125 of the switch is not restricted to flash-lights. Likewise, the illustrative example of an embodiment of the invention imposes no restriction on the scope of the invention, the latter being defined solely by the appended claims.

I claim:

1. A switch mechanism comprising an elec- 130

trically conductive housing, a contact in circuit therewith, a conductor, means for reciprocating the contact along a path at all times intersecting the conductor, and rotatable means whereby the contact may be locked in fixed circuit-closing position with respect to said conductor.

2. A switch mechanism comprising a conductive push button contact electrically connected thereto and rotatable into an adjusted position and reciprocable along a path substantially parallel to its axis of rotation, a conductor at all times disposed beneath said contact, and means for locking said contact in fixed circuit-closing and circuit-opening positions with respect to said conductor.

3. A switch mechanism comprising superposed rotatable plates reciprocable along a path substantially parallel to their axis of rotation, a contact carried by the lower of said plates, a conductor adapted to be engaged by said contact, a fixed plate intermediate of said superposed plates, and cooperating means upon the fixed and rotatable plates for securing the contact in a plurality of adjusted positions.

4. The invention according to claim 3, in which the cooperating means comprise conical cavities in said fixed plate and trough-shaped depressions in said lower rotatable plate, the walls of the cavities having a sliding fit in the depressions.

5. The invention according to claim 3, in which the cooperating means comprise conical projections extending upwardly from said fixed plate and elevated portions on the upper plate adapted to receive the projections.

6. A switch mechanism comprising superposed rotatable plates reciprocable along a path substantially parallel to their axis of rotation, a contact carried by the lower of said plates, a conductor adapted to be engaged by said contact, a fixed plate intermediate of said superposed plates, and cooperating means upon the fixed and rotatable plates for securing the contact in a plurality of adjusted positions, such cooperating means comprising conical projections extending upwardly from said fixed plate and elevated portions on the upper plate adapted to receive the projections, such elevated portions comprising rounded bosses adapted to snap over said conical projections and elongated elevations having a sliding fit with said projections.

7. A switch mechanism comprising superposed rotatable plates reciprocable along a path substantially parallel to their axis of rotation, a contact carried by the lower of said plates, a conductor adapted to be engaged by said contact, a fixed plate intermediate of said superposed plates, and circular series of members upon each of said plates equidistant from the axis of rotation,

said members being adapted to interfit to hold the contact in a plurality of adjusted positions.

8. A switch mechanism comprising a conductor, a symmetrical contact member, and a plurality of guiding means symmetrically disposed about said contact member and adapted to force it into adjusted circuit-closing position.

9. A switch mechanism comprising a spring-supported push-button, a contact plate supported thereby and having a recess, a contact member carried by said plate, a fixed plate having a depressed portion adapted to be received in said recess, means for rotating said contact plate beneath said fixed plate, and a conductor so spaced from the contact member that the circuit is closed when the switch is rotated to bring said recess and depressed portion out of register.

10. A switch mechanism comprising a spring supported push-button, a rotatable plate supported thereby and having a boss, a contact member rotatable with said plate, a fixed plate having a projection adapted to fit into said boss, means for rotating the rotatable plate into such position that the projection and boss engage, and means for preventing depression of the button when said parts are so engaged.

11. An adjustable switch mechanism comprising a rotatable plate, a push-button having a contact member and carried by said plate, said button being depressible with respect to the plate in one adjusted position, a conductor, and means for preventing depression of the contact member whereby the same is locked out of contact with the conductor.

12. The invention according to claim 11, in which means are provided for forcing said contact member into lasting engagement with the conductor.

13. A switch mechanism comprising a conductor, a symmetrical contact member rotatable above said conductor and depressible into engagement therewith and means associated with the contact member whereby upon rotation it will be either forced into contact with the conductor or held out of contact therewith, according to the direction of rotation.

14. A switch mechanism comprising a conductor, a symmetrical contact member rotatable above said conductor and depressible into engagement therewith, and means for propelling the contact member into fixed circuit-closing and circuit-opening relation to said conductor when said contact member is rotated.

15. An adjustable switch mechanism for battery hand lamps comprising a conductor, a push-button opposed thereto, a contact member carried by said push-button and overlying the conductor in all adjusted posi-

tions of the switch, and means for rotating said push-button into a position where it will be sustained against depression.

16. An adjustable switch mechanism for 5 battery hand lamps comprising a conductor, a push button opposed thereto, a contact member carried by said push button and overlying the conductor in all adjusted positions of the switch, and means for rotating 10 said push-button into a position where it will be held in depressed position ~~against~~ the conductor.

17. The invention according to claim 16, in which means are provided for sustaining the contact member against depression. 15

18. A switch mechanism for battery hand lamps, comprising a push button, a symmetrical contact member carried thereby, a disc through which said push button passes and by which it may be rotated, and means 20 for securing the contact member in fixed position.

In testimony whereof, I affix my signature.
LEE J. VOORHEES.
